UNITED STATES PATENT OFFICE.

VINTON ULRIC DAHLGREN PIERCE, OF WASHINGTON, DISTRICT OF COLUMBIA;
JOSIAH PIERCE, EXECUTOR OF SAID VINTON U. D. PIERCE, DECEASED.

AEROPLANE ENGINE.

Application filed February 23, 1918. Serial No. 218,803.

This invention relates to internal combustion engines, and particularly to such engines designed for aeroplanes.

The power developed by an ordinary engine of fixed compression ratio becomes less as the height of the machine above sea level increases. This reduction in power is due to two causes, first, that the pressure of the atmosphere becomes less as high altitudes are attained and, second, that owing to the lower density of the air at great heights, the mass of the mixture drawn into the cylinders during one induction period is less than when the machine is on the ground.

With these facts in view, the general object of this invention is to provide means whereby the cylinders of an internal combustion engine may be charged by forced induction and to provide means whereby the same compression pressure may be secured at different heights, that is to say, means whereby a compression pressure of 5 to 1 for instance may be secured at ground level or up to 10,000 feet altitude, and whereby a compression pressure of 6 or 7 to 1 or greater amount may be secured at altitudes higher than 10,000 feet.

A further object of this invention is to provide means whereby the compression pressure may be varied to any desired degree to correspond with changes in altitude.

Still another object is to provide in an internal combustion engine having a carbureter and a direct connection from the carbureter to the cylinders, a pump having a cubic capacity greater than the cubic capacity of any one of the cylinders, and provide means whereby at the will of the operator, the charge may either be drawn by the ordinary suction of the cylinders direct from the carbureter into the cylinders or whereby the charge may be drawn by means of the pump from the carbureter and then forced into the cylinders at a greater pressure than atmospheric, thus not only securing forced induction but drawing into the pump a greater amount of fuel charge than could be drawn into any one of the cylinders and then forcing this charge of greater bulk into the working cylinder of the engine, so as to secure a proper compression of the charge.

A further object is to provide in a pump

of this character, means whereby the length of the stroke of the piston may be adjusted while the engine is running so that the capacity of the pumping cylinder, and therefore the effective cubic capacity of the pumping cylinder, may be controlled, thereby to control the ratio of compression at different altitudes.

Other objects will appear in the course of the following description.

My invention is illustrated in the accompanying drawings, wherein:—

Figure 1 is a side elevation of an aeroplane engine provided with my improved pump;

Figure 2 is a rear elevation of the engine, the pump being in section;

Figure 3 is a longitudinal sectional view through a pump cylinder and crank case showing means whereby the stroke of the piston may be increased or reduced;

Figure 4 is a fragmentary sectional view through the shaft 41 transverse to the axis of the shaft;

Figure 5 is a like view to Fig. 3 but showing another manner of increasing or decreasing the throw of the pistons;

Figure 6 is a fragmentary side elevation of an aeroplane engine constructed in accordance with my engine and showing means whereby the inlet of air to the carbureter may be adjusted, in correspondence with the adjustment of the throw of the pistons;

Figure 7 is a section on the line 7—7 of Figure 6; and

Figure 8 is a sectional view of the valve casing 32 and the valve therein showing the valve in position when the fuel is sent directly from the carbureter to the engine cylinders.

In the drawings, I have shown an ordinary type of aeroplane engine, such as is used today on the best and most powerful aeroplanes. In this case, the cylinders 10 are disposed in two rows in angular relation to each other. I have illustrated an eight-cylinder engine, but of course my invention is not limited to this, nor is it limited to the precise arrangement of any engine cylinders. Each cylinder is provided with the usual intake and outlet ports controlled by the usual valve. Inasmuch as this valve mechanism is well known, it therefore re-

quires no specific description. The valves are preferably operated by means of a cam shaft, in the usual manner. The main shaft of the engine is designated 11 and has, at its 5 forward end, the propeller blade mounting 12, which also may be of any suitable construction.

For the purpose of supplying fuel to the cylinders of the internal combustion engine, 10 I provide the usual carburetors 13, each connected by a supply pipe 14 to the manifold 15 which connects to all of the cylinders on one side. So far this engine is precisely the same as any aeroplane engine.

15 For the purpose of securing a forced induction and a proper compression of the fuel charge at high altitudes, I provide, in types of engines having double rows of cylinders, the pumping cylinders 16. These, 20 as illustrated in Figure 2, have conjoined crank cases 17 as they may be called. At its outer end, each cylinder is provided with an inlet port 18 and an outlet port 19, these 25 ports being governed by the valves 20 and 21 respectively. These valves in turn are governed by any suitable mechanism and I have 30 illustrated for this purpose the ordinary valve operating mechanism common in internal combustion engines, comprising a rocker 22 pivoted intermediate its ends and contacting alternately with the stems of the valves 20 and 21. This rocker arm is operated by means of a rod 23 in turn connected to a suitable cam mechanism (not 35 shown), this cam being of well known design, such as is used for controlling the opening and closing of the ordinary valves of the engine.

40 Operating in each of the cylinders 16 is a piston 24 which is connected by the piston rod 25 to the crank shaft 26 mounted in suitable bearings in the walls of the crank case 17. This crank shaft 26 is illustrated 45 as having mounted upon it a sprocket wheel 27, from which a sprocket chain 28 passes around a sprocket wheel 29 mounted upon a counter shaft 30 driven from and operatively connected to the main driving shaft or crank shaft of the engine. I do not, of 50 course, wish to be limited to this particular means of transmitting power from the engine shaft to the pump pistons.

55 Each cylinder 16 has a cubic capacity greater than the cubic capacity of any of the cylinders 10 with which it coacts. The pump cylinder 16 for instance may be $\frac{1}{3}$ larger in cubic capacity or $\frac{1}{2}$ larger than the coacting cylinders 10, depending upon the compression pressure which is desired 60 to be secured. Connected to the pipe 14 just above the carburetor 13 is a branch pipe 31 which extends to the inlet port 20 of the corresponding cylinder 16 and disposed at the junction of the pipes 14 and 31 is a directing 65 valve of any suitable form, whose casing is

designated 32, this valve being illustrated as provided with an arm 33 connected to a controlling rod 34 in turn connected to any suitable actuating means. When this valve is turned in one direction, the charge is 70 allowed to pass directly from the carburetor 13 to the coacting manifold and cylinders and when the valve is turned to another position, this direct connection is cut off and the charge is directed into the pipe 31, 75 and thus into the pumping cylinders. Leading from the outlet port 21 of each pumping cylinder is an outlet pipe 35 which communicates with the manifold 15 preferably at its middle. This pipe 35 is provided with a valve 36 designed to cut off the pump from its connection with the manifold 15 and open communication between the pump cylinder and the air, such a valve being 80 illustrated in Figure 8.

85 As illustrated in Figure 8, the valve 32 (and this applies equally well to the valve 36) is so arranged as to cut off the pump from connection to the carburetor (or the engine with relation to the valve 36) and at this time to connect the pump with a source of air so that the pump will simply 90 operate idly. This is secured by providing a rotatable valve 32^a and providing a vent port 32^b which, when the valve is turned so as to connect the carburetor directly with the pipe 14, will connect the pipe 31 with the open air. Of course the valve 36 is turned to correspond with the valve 32^a and 95 connect the pipe 35 with the open air when the connection between the pipe 35 and the manifold is cut off. Any suitable valve arrangement may be used for this purpose. It is, of course, to be understood that a 100 throttle valve of the usual type is disposed in connection with the carburetor and between the carburetor and the valve casing 32 so as to control the passage of fuel either to the pipe 14 or to the pipe 41 in the usual manner.

105 It will be obvious now that under ordinary circumstances and when the machine is say below the 10,000 foot level, the valve 32 will be shifted so that the fuel charge will pass directly from the carburetor to the manifold 15 and thence into the engine cylinders, but that when the machine has risen above the 10,000 foot level or at any other predetermined altitude, this valve 32 is shifted so as to cause the pump to draw a relatively large charge from the carburetor into the pump and then force this charge into the manifold 15, and thence into the engine cylinders at a pressure 115 greater than the atmospheric pressure at the level at which the machine is flying. Thus, though the atmospheric pressure may be very greatly reduced, as for instance one-third at a level of 10,000 feet, yet if the 120 cubic capacity of the pump is a third greater 125

than the cubic capacity of the cylinder, the compression pressure within the cylinder will be the same as when the machine was at ground level or below the 10,000 foot altitude. In other words, the mass of the mixture drawn into the cylinder during the induction period is greater than when the machine is on the ground in proportion to the height of the machine and hence the 10 heat value of the charge is the same at the 10,000 foot level as it is at the ground level, and eliminating air resistance and lift and the resistance of the air to the action of the propellers, in other words, the thrust of the 15 propeller, the engine will exert as much power at the 10,000 foot level as it will below the 10,000 foot level.

Under ordinary circumstances, a fighting aeroplane flies at an average altitude of 20 about 10,000 feet. Hence provision need only be made, to secure proper induction and compression below the 10,000 foot level and on an average of about 10,000 feet. It is obvious, however, that if means are provided for still further adjusting the effective capacity of the pumping cylinder, that adjustments may be made for many levels or altitudes.

In Figures 3 and 4 I have illustrated 30 means to this end, wherein this adjustment of the effective capacity of the pumping cylinders is secured by adjusting the length of the stroke of the pumping piston. In this case the pumping piston 24 is connected 35 to an eccentric rod 37, connected to an eccentric ring 38 of any suitable or usual form and reciprocated by means of an eccentric 39 which is of usual form except for the fact that it is diametrically slotted, the slot 40 being designated 40. Through this slot, the shaft 41 passes, this shaft corresponding to the crank shaft 26. The shaft 41 is squared at that portion which engages with the walls of the slot 40 or is otherwise formed to cause 45 a rotation of the eccentric without, however, preventing the shifting of the eccentric in a direction radial to the shaft 41. The shaft 41 is driven by means of a sprocket wheel 42 in turn engaged by the sprocket wheel 27 previously referred to and this shaft 41 is 50 hollow and has bearing in the walls of the crank case 17.

Slidably operating within the shaft 41 is 55 a slide 43 which is illustrated as provided with a pair of cam slots 44 extending in the same direction and being disposed one ahead of the other. The interior of the shaft 41 is formed with guide slots or grooves 45 for the slide 43, the slide 43 having an easy 60 movement in these guide grooves. The slide 43 has a centrally disposed extension or rod 46 extending out through a cap 47 at one end of the shaft, and means are provided for longitudinally shifting the slide 65 43 which includes a grooved disk or collar

48 on this shaft engaged by the usual shipper ring 49 in turn connected to a lever or other suitable operating device. It will be obvious now that the extension 46 of the slide may rotate within the shipper ring 49, but that the shifting of the shipper ring will shift the slide from one end of its stroke to the other.

Pivottally connected to the end walls of the slot 40 in any suitable manner are links 50, these links passing inward through slots in the shaft 41 and being provided with pin 51 carrying rollers 52 engaging with the walls of the corresponding slot 44. It will be obvious now that as the slide 43 is shifted toward the left (assuming the position of the parts illustrated in Figure 3), the shipper ring will be urged to a position of relatively great eccentricity with relation to the shaft 41 and that as the slide 43 is urged in the opposite direction, the ring will be shifted into a position of less eccentricity. When the slide 43 is shifted to the extreme left as it is in Figure 3, it will be obvious that the stroke of the piston will be increased and therefore the current or volume of the charge will be increased and that in effect this adjustment of the length of stroke is no more or less than adjusting the effective cubical capacity of the pumping cylinder. It will, of course, be understood that the operating means connected to the shipper ring 49 will operate over a scale so that the operator will know to what extent he has adjusted the cubic capacity of the pumping cylinder. Inasmuch as the throw of an eccentric is relatively small in comparison with the crank, it will be necessary to increase the diameter of the pumping cylinder and the piston over the case where a crank is used.

In Figure 5, I illustrate a form of variably adjustable crank, which may be used in connection with a pump. In this figure 110 I have illustrated the pump cylinder 16 and its crank case 17. Passing through it is the crank shaft 27. Operating in the cylinder is the piston 24 with its connecting rod 25. The crank shaft 27 is formed in two sections having outwardly extending crank arms 53 which are longitudinally slotted as at 54 and operating in these two slots are the sliding blocks 55 carrying the wrist pin 56 to which the connecting rod 25 is engaged. Sliding upon the crank shaft 27 on each side of the crank are the collars 57, these collars being connected by links 58 to the blocks 55, the links being pivoted to the blocks and to the collars. The collars 57 are splined or otherwise engaged with the blocks to rotate therewith and are provided with shipper rings 59. For the purpose of operating these shipper rings and thereby shifting the collars 57 longitudinally of the shafts in 115 opposite directions, I may provide any suit- 120 125 130

able mechanism, but I have illustrated a transversely extending actuating shaft 60, carrying gear wheels 61. Operatively supported in any suitable manner are the screw-threaded rods 62, each of which engages one of the shipper rings 59. These screw-threaded rods pass through fixed nuts 63 and carry the gear wheels 64 which mesh with the gear wheels 61. The rods are screw-threaded in opposite directions and hence it will be obvious that upon a rotation of the shaft 60, the screws 62 will be rotated in opposite directions so as to shift the shipper rings toward or from each other and thereby 10 change the angles of the rods 58 and shift the wrist pin supporting blocks outward or inward relative to the axis of the crank shaft. The shaft 60 can be rotated either directly by hand or through reducing gears, 15 and I have illustrated the shaft 60 as being provided with a handle 65 operating over an indicating dial 66 graduated to correspond with the graduations of the barograph, so that when the latter instrument indicates 20 a certain height, the aviator may shift the handle 65 to the corresponding numeral on his dial 66 and know that the stroke of the piston has been adjusted to correspond with the altitude. This mechanism, of course, 25 accomplishes the same end as is accomplished by the use of the adjustable eccentric, that is, the end of providing means for adjustably controlling the compression pressure at various altitudes.

30 35 It will be noted that with my system of forced induction, and by the use of a pump having a larger cubic capacity than the cubic capacity of the cylinder, I secure not only the necessary compression pressure at a predetermined altitude to compensate for the rarity of the atmosphere at this altitude, but that I also draw into the pump a sufficient volume of gas to compensate for the reduction in air pressure. In other words, 40 45 if I simply increase the throw of the piston so as to secure additional compression pressure, I would not increase the suction power of the cylinder, but by providing for a positive induced feed of fuel into the engine cylinder, I compensate for this reduction of air pressure at the high altitude and at the same time secure the necessary compression pressure in the cylinder corresponding to this altitude.

50 55 While I have illustrated particular embodiments of my invention, I wish it understood that the principle of the invention may be embodied in other forms and that I do not wish to be limited to the details illustrated, either as to the form of the pump, its connections to the engine and carbureter, or to the means whereby variable throw of the pump piston is secured.

60 65 It is, of course, advisable to increase the amount of air passing through the carburet-

er as the machine rises to higher altitudes and in order that this amount of air may be increased relative to the gasoline, to thus reduce the richness of the mixture, as the machine rises and as the throw of the pistons is adjusted, I may provide a carbureter with the air inlet ports 67 and may provide a rotary annular valve 68 having air ports 67 which are adapted to register with or be placed more or less out of register with the air ports 67. I have illustrated this valve as an annulus mounted upon the lower end of the carbureter and having an arm 69 connected by means of a rod 70 to a lever 71, the upper end of which lever is operatively connected to the screw rod 62 at the rear end of the engine. Thus, it will be obvious that as the piston stroke is reduced, the amount of air entering the carbureter will be likewise reduced and that as the piston stroke is increased, the amount of air entering the carbureter will be correspondingly increased.

It is particularly to be noted that I do not change the form of the engine in any way but that I merely add to the engine a pump of a particular character. Thus, my invention may be applied to all forms of internal combustion engines designed for flying machines and may be applied, without any change in the valve mechanism, the form or character of the cylinders, or the manner, in which the pistons are connected to the crank shaft of the engine. The invention forming the subject matter of this application constitutes an improvement on the construction illustrated in my co-pending application, Serial No. 178,692, filed on the 5th day of July, 1917.

Having described my invention, what I claim is:—

1. An internal combustion engine including a multiplicity of cylinders each having a piston therein, a carbureter, a direct connection between the carbureter and the cylinders, a reciprocating pump geared to make two reciprocations to one of a piston and arranged to supply fuel mixture at substantially maximum pressure in synchronism with the suction stroke of each cylinder, a connection between the pump and the carbureter and between the pump and each of the cylinders, and means for directing the charge from the carbureter either directly to the cylinders or cutting off the direct connection between the cylinders and carbureter and connecting the carbureter with the pump.

2. An explosion engine including a multiplicity of cylinders and pistons working therein, a carbureter therefor, means for conducting a charge from the carbureter directly to the cylinders, a reciprocating pump geared to make two reciprocations to one of each piston and arranged to supply a

fuel mixture at substantially maximum compression in synchronism with the suction stroke of each piston, said pump having a greater capacity than that of any of the 5 cylinders and connected thereto, and means for directing the charge from the carbureter either directly into the cylinders or into the pump and thence to the cylinders.

3. An internal combustion engine having 10 a plurality of cylinders a manifold therefor, a carbureter, a reciprocating pump geared to make two reciprocations to one of each piston and arranged to supply a fuel mixture at substantially maximum compression 15 in synchronism with the suction stroke of each piston, said pump having a capacity greater than the capacity of any one of the cylinders, and means for directing fuel from the carbureter directly into said manifold 20 or into said pump.

4. An internal combustion engine, comprising a plurality of cylinders and pistons working therein, crank shafts connected to said pistons, a charge forming device, a reciprocating pump geared to make two reciprocations to one of each piston, said pump having capacity greater than any one of the 25 cylinders and operated by said crank shaft in synchronism with said engine, and means 30 for directing a charge either directly from the charge forming device to said cylinders or from the charge forming device to the pump and so to the cylinders.

5. An internal combustion engine for 35 aeroplanes including a plurality of cylinders, pistons therein, a crank shaft operatively driven from the pistons, a charge forming device, a pump including a pump cylinder, the pump being driven by the crank shaft, 40 and the cylinder having a cubic capacity greater than the cubic capacity of any one of the cylinders of the engine, a direct tubular connection from the charge forming device to the cylinders, a tubular connection 45 from the charge forming device to the pump and from the pump to said cylinders, and valves shiftable to direct the charge from the charge forming device directly to the cylinders, or into said pump and thence to 50 the cylinders, said valves when in a position to cut off the pump from the charge forming device and cylinders providing air inlets and outlets to and from the pump.

6. An internal combustion engine comprising a plurality of cylinders and pistons working therein, a charge forming device, and an independent reciprocating pumping means geared to make two reciprocations to one of a piston and to operate in synchronism with each piston to supply a fuel mixture at substantially maximum pressure with the suction stroke of each piston; a direct connection being provided from said charge forming device to said cylinders and a bypass connection by way of said pumping 65

means, and means for variably controlling the stroke of the piston while the pumping means is in operation.

7. The combination with an internal combustion engine having a cylinder, of a charge 70 pump including a cylinder operatively connected to the cylinder of the engine and to a source of fuel, a piston operating within the pump cylinder, a carbureter supplying fuel to the pump cylinder and having an air 75 inlet, means for adjusting the effective stroke of the piston while the pump is running, a valve controlling the air inlet to the carbureter, and an operative connection between said valve and said means whereby the 80 amount of air inlet may be cut down when the stroke of the piston is decreased, and increased when the stroke of the piston is increased.

8. The combination with an internal combustion engine having an explosion chamber and a carbureter, of pumping means adapted to supply a fuel mixture at substantially maximum compression synchronously with the suction stroke, means for variably adjusting the compression of gases within the explosion chamber, and means automatically regulating the amount of air entering the carbureter proportionately to the adjustment 90 of the compression within the explosion 95 chamber.

9. In an internal combustion engine, the combination with an explosion cylinder, of a charge pump including a cylinder operatively connected to the explosion cylinder, 100 a piston moving in the pump cylinder, means for variably adjusting the throw of the piston, and a carbureter coacting with the pump cylinder and having an air inlet, and means for automatically regulating the 105 amount of air entering the carbureter in proportion to the adjustment of the piston throw.

10. An internal combustion engine including an explosion cylinder, a pump cylinder operatively connected to the explosion cylinder, a piston operating in the pump cylinder, a carbureter having an air inlet opening, a valve controlling the air inlet opening, means for causing a reciprocation 110 of the piston including an element movable to increase or decrease the throw of the piston, and operative connections between said air valve and said element whereby to shift the air valve in correspondence with 115 the adjustment of the piston throw.

11. A multiple cylinder multi-cycle internal combustion engine having cylinders with reciprocating pistons therein, a source of fuel supply, a direct connection from the fuel supply to the cylinder, a pumping device of the reciprocating type geared to make two reciprocations to one of each piston and arranged for supplying a fuel charge in synchronism with the suction 125 130

- stroke of each piston, a by-pass connection from the fuel supply to the cylinder by way of the pumping device, and means for cutting in and cutting out the direct or by-pass connection. 45
12. In a multiple cylinder internal combustion engine, the combination with the intake manifold and the carburetor, of a reciprocating pump between the carburetor and the manifold for increasing the quantity of mixture injected into each cylinder, means to lengthen at will the stroke of the pump thereby to increase the charge injected by the pump and the compression of the charge to compensate for reduced air pressure and lessened density of the charge at high altitudes, and means for automatically regulating the amount of air entering the carburetor in proportion to the increase in the stroke of the pump. 50
13. An internal combustion engine comprising a plurality of cylinders and pistons working therein, a charge-forming device, and pumping means for supplying a fuel mixture for each cylinder of a density in excess of that which would normally be drawn into the cylinder on the suction stroke thereof, a direct connection being provided from said charge-forming device to said cylinders and a by-pass connection by way of said pumping means, and means for variably controlling the delivery capacity of the pumping means in operation. 55
14. The combination with an internal combustion engine having a cylinder, and a fuel-source, a force-feed-charge-delivering device connected to the cylinder of the engine and to the source of fuel, means for adjusting the effective delivering capacity of the force-feed-device independent of engine speed, a valve controlling the air inlet to the fuel-source, and an operative connection between said valve and said means whereby the amount of air admitted to the fuel source may be varied as the capacity of the force-feed device is varied. 60
15. An internal combustion engine including a plurality of cylinders, pistons therein, a crank shaft operatively driven from the pistons, a charge-forming device, a charge-delivering pump operated in any suitable manner and having a positive fuel delivering capacity in excess of the fuel-suction capacity of the cylinders on each suction stroke of the engine, a direct connection from the charge-forming device to the cylinders, a connection from the charge-forming device to the pump and from the pump to said cylinders, means to direct the charge from the charge-forming device directly to the cylinders, or into said pump and thence to the cylinders, and atmospheric cut-in and cut-out valves, one on the intake and the other on the delivery side of said charge delivering pump. 65
16. The combination of an internal combustion engine, a carburetor, a manifold, a force-feed for the carburetor, means for cutting the force-feed in or out of connection with the carburetor and into and out of connection with atmosphere, and means for varying the positive delivering capacity of the force-feed during its operation and independently of engine speed. 70
17. The combination of an internal combustion engine, a source of fuel supply, means for delivering the fuel supply to the engine under normal suction action of the engine, force-feed means for delivering the fuel to the engine on each of its suction strokes in an amount in excess of the suction capacity of the piston, and means on the intake and delivery sides of said force-feed device for connecting it partially or wholly with the atmosphere. 75
- In testimony whereof I hereunto affix my signature.
